ADJUSTABLE PILOT

James L. Breese, Santa Fe, N. Mex., assignor to
Oil Devices, Santa Fe, N. Mex., a limited partnership of Illinois

Application March 17, 1939, Serial No. 262,419

3 Claims. (Cl. 158—91)

My invention relates to an improvement in pilot dampers or baffles for use for example in pot type burners.

One purpose is the provision of an improved 5 pilot baffle which permits the maintenance of a pilot flame in a pot with a maximum turndown when a heating effect is not desired.

Another purpose is the provision of improved 10 means for maintaining a relatively small pilot flame located off the center of the pot and, preferably, opposite a liquid fuel inlet.

Another purpose is the provision of improved 15 means for varying the cross sectional area of the aperture connecting the lower and the upper part of a pot, in connection with a pilot structure.

Another purpose is the provision of thermostatic means for varying the cross sectional area 20 of such an aperture.

Other purposes will appear from time to time 25 in the course of the specification and claims.

I illustrate my invention more or less diagrammatically in the accompanying drawings wherein:

Fig. 1 is a vertical central axial section through 25 a pot and burner, illustrating my invention with the pilot shutter in inoperative or full combustion position;

Fig. 2 is a partial view looking in the direction of arrows 2—2 of Fig. 1;

Fig. 3 is a section taken on the line 3—3 of 30 Fig. 1, with the pilot shutter in operative position; and

Fig. 4 is a section taken on the line 4—4 of 35 Fig. 1, with the pilot shutter in operative position.

Like parts are indicated by like characters 40 throughout the specification and drawings.

Referring to the drawings, 1 generally indicates any suitable shell or heater housing, the details of which do not of themselves form part of the present invention. If desired, a further outer 45 housing 2 may be employed. 3 is a flange extending circumferentially about the interior of the shell 1. Mounted on this flange 3, I illustrate a generally cylindrical pot 4 having a bottom 5 and an oil or liquid fuel inlet 6.

45 A plurality of primary air inlets are located in the pot 4, the lower row being illustrated as at 7, and the remaining rows being indicated as at 8.

A preferably fixed pilot ring or baffle 9 is 50 mounted on any suitable pins or supports 10, above the lowest rows or primary air inlets 7. This ring has a large central aperture 11, which may be partially closed by a shutter or damper 12, which is shown as having bearing pins or pivots 13, 14 at opposite sides thereof. These may

seat in any suitable bearing sleeves or half sleeves 15, 16.

17 is any suitable centering or positioning ring on the member 14, which prevents unintended longitudinal movement of the shutter 12 in the 5 bearings. A rod 18 extends from the bearing pin 13 through the wall of the pot 4 and the shell 1 and is provided with an exterior washer 19, which may be engaged by any suitable bracket 20 on the exterior of the shell member 1 in order further to hold the rod 18 in proper position. 21 is another washer or clutch element mounted on the rod 18 and held against movement in relation thereto.

Rotatably mounted on the rod 18 is the clamp 15 disc 22, with its lever arm 23. 24 is a spring which normally urges the disc 22 against the fixed disc 21, thereby frictionally holding the disc 22 against movement in relation to the rod 18. 25 is any suitable abutment member, washer or the like, for 20 maintaining the spring 24 properly compressed, the washer being screw-threaded if necessary, or otherwise adjustably mounted on the rod 18.

Pivoted to the outer end of the arm 23 is a link 26, which in turn is pivoted to an arm 27 25 associated with a rotated stem 28, which passes through the disc end or closure 29 of a housing 30, in the inner end of which it is further mounted, as in the bearing sleeve 31.

32 is a bimetallic helix secured at one end to 30 the rod 28 and at its opposite end to the housing 30. The housing 30 extends into the interior of the burner, within the shell 1 and above the pot 4, and is therefore responsive to heat conditions within the burner. It will be understood that the 35 bimetallic helix 32 will flex in response to temperature changes and that this flexure, through the lever 27, the link 26 and the lever 23, will cause a rotation of the shutter 12 into and out of pilot position.

The pot 4 may be open topped as at 35, or if desired a top baffle 36 may be mounted thereon. 37 indicate secondary air apertures for supplying secondary air for the final completion and combustion of the mixture preliminarily formed by 45 the admission of primary air through the apertures 7 and 8 to the vaporized liquid hydrocarbons.

It will be realized that whereas I have described and illustrated a practical and operative device, nevertheless many changes may be made in the size, shape, number and disposition of parts without departing from the spirit of my invention. I therefore wish my description and my drawings to be taken as in a broad sense illustrative or 50 55.

diagrammatic, rather than as limiting me to my precise showing.

The use and operation of my invention are as follows:

5 In the employment of pot type burners a maximum heating efficiency in connection with a low turndown is desirable. I find it particularly desirable to provide a separation between a lower or pilot zone in the pot, below the ring 9, and 10 an upper or normal mixing zone above the ring 9. However, the ring 9 has an aperture so large that of itself it is ineffective to provide the pilot effect. In other words, in normal maximum operation of the device, the ring 9 has no substantial effect on mixing or combustion conditions and merely serves to cooperate, when a minimum turndown is desired, with a movable or adjustable damper or shutter 12.

Whereas I have described thermostatic or automatic operation of the member 12, I illustrate in dotted line in Fig. 1 manually controlled means 40, it being understood that the damper may be controlled either thermostatically or manually. Under some circumstances I may find 25 it practical to combine both features in one structure. It will be understood, of course, that a release of the spring 24, for example by a loosening of the washer 25, will render the thermostatic control inoperative while leaving the 30 manual control 40 in full operation.

Whether manual or thermostatic operation is employed, however, it will be understood that when the device is operated on a pilot basis, with a minimum flame, the shutter 12 is in horizontal position, as illustrated in full line in Fig. 4, and defines, along its straight edge 12a, an eccentric aperture of substantially smaller cross sectional area than the circular aperture defined by the inner edge of the ring 9. This aperture, and the pilot flame which comes upwardly therethrough, is off center in relation to the central axis of the pot. It is preferably placed opposite the oil inlet so that the gases travel the full width of the burner before coming out through the orifice so provided.

45 A frequent trouble of pilots with a central burner is that the side opposite the oil pipe is relatively lean, and the air from that side is liable to cause incorrect combustion. This drawback has been obviated by the above described structure.

It will be understood of course that when the damper 12 is turned in the position in which it is shown, for example in Fig. 1, and in dotted 50 line position in Fig. 4, it is, as it were, entirely out of use. The area within the ring 9 is so great that the combustion taking place in the upper portion of the pot 4 or above the top of

the pot is effective to vaporize the inflowing oil in the bottom of the pot without any substantial shielding effect. Thus, I am able to obtain a maximum turndown or pilot effect with a minimum interference with the efficiency of the 5 burner.

It will be understood in any event that the ring or fixed baffle 9 is only incidental in the function of the pilot and is a mere matter of convenience as providing, in connection with its 10 central aperture and the baffle 12, a variable communicating space between the upper and lower portions of the pot 4. In the pot shown in the present application it is convenient to employ a ring or fixed baffle since, if a shutter with 15 a full diameter were used, the cutoff portion 12a might have to be too large in order to make it swing to the vertical position on high fire. The ring need not play any functional part in the operation of the pilot.

20 I claim:

1. In a pot type burner, a pot having a wall with a plurality of primary inlet apertures therein, a fixed pilot ring located in said pot above the lowest primary air inlet apertures, a shutter 25 pivotally mounted in the aperture of said ring, said shutter being adapted to define an eccentrically located pilot aperture, and a liquid fuel inlet means for said pot, located below said pilot structure, said means communicating with the 30 pot at a point remote from said pilot aperture.

2. In a pot type burner, a pot having a wall with a plurality of primary inlet apertures therein, a fixed pilot ring located in said pot above the lowest primary air inlet apertures, a shutter 35 pivotally mounted in the aperture of said ring, said shutter being adapted to define an eccentrically located pilot aperture, and liquid fuel inlet means for said pot, located below said pilot structure, said means communicating with the 40 pot at a point generally diametrically opposite to said pilot aperture.

3. In a pot type burner, a pot having a wall with a plurality of air inlet apertures therein, a pilot baffle structure located in said pot adjacent the lowest primary air inlet apertures, including a horizontally pivoted shutter, one side of 45 said shutter being formed to provide an eccentric passage when the shutter is in generally horizontal position, said baffle having an eccentric 50 pilot aperture, and a liquid fuel inlet means for said pot located below said baffle structure and communicating with the pot at a point sufficiently remote from said pilot aperture to permit hydroxylation of the fuel admitted therethrough prior to the escape of such fuel in vaporized form through the pilot aperture.

55 JAMES L. BREESE.
